CLAIM

The ornamental design for a modular electrochemical apparatus, as shown and described.

DESCRIPTION

FIG. 1 is an isometric view of a modular electrochemical apparatus showing the new design;

FIG. 2 is a front view of the modular electrochemical apparatus;

FIG. 3 is a back view of the modular electrochemical apparatus;

FIG. 4 is a right side view of the modular electrochemical apparatus;

FIG. 5 is a left side view of the modular electrochemical apparatus;

FIG. 6 is a top plan view of the modular electrochemical apparatus; and,

FIG. 7 is a bottom plan view of the modular electrochemical apparatus.

The broken lines shown represent the portions of the modular electrochemical apparatus that form no part of the claimed design.
